UNITED STATES PATENT OFFICE

2,193,813

FRONT SIGHT TIGHTENING TOOL

Clarence E. Harris, Winthrop, Mass.

Application June 3, 1938, Serial No. 211,597

1 Claim. (Cl. 81—15)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a front sight tightening tool and more particularly to such a tool for resetting the fixed stud of the front sight used on army rifles.

Continuous use of a rifle causes the movable part of the sight to be struck more or less often, such as when placing the rifle in or removing it from an arms rack, with the result that the material of the fixed stud becomes sprung, thereby widening the dovetail groove in such stud and consequently loosening the movable stud.

While devices are now in use for restoring the fixed stud to its original shape and position the present device aims to restore the fixed stud to thereby tighten the movable stud without the removal of any of the elements of the sight, and in such manner that the fixed stud is more firmly locked to the gun barrel.

With the foregoing and such other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a side elevation partly in section and with parts removed of the tool applied to a rifle barrel preparatory to tightening the sight;

Fig. 2 is a similar view showing relation of the parts during tightening of the sight;

Fig. 3 is a plan view of the tool, parts broken away;

Figs. 4, 5 and 6 are sections on the respective lines of Fig. 1;

Fig. 7 is a detail perspective view of the eccentric for mounting the resetting element;

Figs. 8 and 9 are respectively a plan and elevation of the hollow die; and

Figs. 10 and 11 are respectively a side elevation and plan of the resetting element.

Referring to the drawing by numerals of reference:

50 A conventional front sight for a rifle barrel A comprises a fixed stud B (Figs. 4 and 5) which is in the form of a sleeve having a longitudinally extending groove C for receiving a key D on the barrel to prevent lateral displacement and having an aperture for receiving a transversely disposed

pin E which engages a groove F in the barrel to prevent longitudinal displacement. The fixed stud B is formed on its upper side with a longitudinal rib G having a transversely disposed dovetail groove H for receiving the dovetail tongue I of the movable stud J carrying the front sight member K. The stud J is held in place in the stud B by a screw L.

The tool for tightening the front sight comprises a frame consisting of spaced links 5—5 offset intermediate their ends to space the front ends of the links a greater amount than the rear ends. A head disposed between the front ends of the links is preferably of two parts, a socket member 6 and a hollow die 7 fitted therein and conveniently held by a set screw 8. The socket member 6 includes a pair of trunnions 9—9 rotatably mounted in apertures 10 of the links and a screw 11 threaded in each trunnion has an enlarged head 12 for engaging the outer side of the corresponding link to maintain the assembly.

The rear face of the die 7 is provided at its upper portion with spaced projections 13—13 and at its lower portions with a projection 14. These projections have a wedge-shaped or beveled edge (Figs. 1 and 2) for engaging the front face of the fixed stud B and upsetting the metal thereof to close it onto the barrel A and secure the stud against longitudinal displacement while at the same time the spaced projections 13—13 which engage the stud on both sides of the key D will upset the metal to remove lateral looseness.

The rear portions of the links 5—5 are provided with aligned apertures 15—15 in which the ends 15^a of a pin 16 are journaled. A screw 17 provided for each end of the pin and threaded therein has an enlarged head 18 for engaging the outer side of the corresponding link to maintain the assembly. The pin 16 includes a centrally positioned eccentric disk 19 and on each side thereof it is formed with non-circular portions 20—20 which serve to space the links and mount the forked ends 21—21 of a lever 22 which is conveniently made in two parts held together by screws 23, only one of which is shown.

A resetting member 24 disposed between the links has a reduced rear end 25 inserted between the forked ends of the lever 22 and it is provided with an aperture 26 for receiving the eccentric disk 19. The member 24 is additionally supported by a pair of laterally projecting pins 27—27 each of which rides in a slot 28 in the corresponding link. The front part of the member 24 is formed with a face 29 for engaging the rear face of the

rib G and it also has a pair of spaced jaws 30—30 for embracing the rib.

In Fig. 1 the tongue I of the fixed stud J is shown as being loose in the groove H due to dis-
5 placement of the metal of the rib G which forms the rear walls of the groove. In order to reset this metal for the purpose of firmly holding the stud J the tool is applied as shown in Fig. 1 whereby the die 7 and resetting member 24 are
10 disposed so as to engage opposite sides of the stud B and the lever 22 is then moved to the rear. This operation on the lever produces rotation of the pin 16 and the eccentric disk 19 ad-
15 vances the resetting member 24 and resets the metal of the rear wall of the groove. This en-

gagement establishes a support during continued operation of the lever whereby the die 7 is re-tracted to squeeze the metal of the front face of the stud B.

I claim:

A tool for tightening a front sight provided with a fixed stud comprising a pair of spaced links, a hollow die for engaging the front face of the stud trunnioned in the links, a pin journaled in the links, and including an eccentric disk, a lever 10 mounted on the pin for rotation therewith, a resetting member for engaging the rear face of the stud slidably supported by the links and in driving engagement with the eccentric disk.
